MECHANICAL BREAKDOWN

Walter H. Beane, Klamath Falls, Oreg.

Application February 8, 1943, Serial No. 475,168

2 Claims. (Cl. 214—8.5)

This invention relates generally to the manufacture and handling of lumber, and particularly to a mechanical breakdown.

The main object of this invention is to construct a mechanical breakdown by means of which a stack of lumber can be unstacked and the boards thereof delivered separately, or in tiers, to a conveyor or to a planer or other machine.

The second object is to construct a machine of the class described which will easily and effectively unstack lumber with the saving of a considerable amount of labor ordinarily employed in such operations.

The third object is to construct a machine of the class described in which the operation is positively performed and in which the tendency to become inoperative is reduced to the minimum amount.

The fourth object is to construct a special form of mechanism which will satisfactorily perform this operation in which there is a low power requirement.

The fifth object is to construct a breakdown which adapts itself to the transfer of the package onto the breakdown from the end as shown, or to transfer the package at right angles by use of floor chains (not shown).

The sixth object is to construct a mechanical breakdown in which the knees are tiltable and in which the guide braces tilt with the knees and prevent the stack from becoming disarranged or collapsing during the tilting operation.

The seventh object is to construct a breakdown in which a varied amount of tilt can be obtained. For example, in order to handle rough lumber, more tilt is required to make the board slide from the load, and with surfaced lumber, less tilt is required, any excessive tilt being objectionable.

These and other objects are accomplished in the manner set forth in the following specification, as illustrated in the accompanying drawings, in which:

Fig. 1 is a fragmentary, vertical section taken along the line 1—1 in Fig. 2.

Fig. 2 is a plan of Fig. 1.

Fig. 3 is a vertical section taken along the line 3—3 in Fig. 2 showing a stack on the breakdown in an upright position.

Fig. 4 is similar to Fig. 3 but showing the stack tilted and partially broken down.

Fig. 5 is a front elevation of a lift arm.

Similar numerals refer to similar parts throughout the several views.

Referring in detail to the drawings there is shown a set of foundation piers 10 upon which are erected the posts 11 which support the cross ties 12 upon which are mounted the stringers 13 which support the floor joists 14 of the deck 15 in which is formed an opening 16.

Mounted on the cross ties 12 are the live rolls 17 whose shafts 18 journal in the bearings 19 and are provided with the sprocket wheels 20 around which pass the drive chain 21. Idler sprockets 22 are provided to maintain a driving relationship between the chain 21 and the sprocket wheels 20. The chain 21 also passes around the sprocket wheel 23 on the shaft 24 around whose sprocket wheels 25 pass the floor chains 26 across which are passed the bunks 27 which support the package 28 which in this particular instance consists of lumber whose individual pieces 29 are placed in parallelism with the floor chains 26. The floor chains 26 are driven from any convenient prime mover (not shown).

The purpose of the mechanism thus far described is to receive a package 28 from a carrier, crane or other source, and carry it by means of the floor chains 26 to the rolls 17. As the first bunk 27 passes over the ends of the floor chains 26, it drops clear of the package 28 which projects over the first roll 17 and is finally transported to a point near the middle of the row of rolls 17.

Underneath the deck 15 is placed a foundation 30 upon which rests the upright posts 31 whose inclined uppermost portions 32 are supported by the braces 33 from the deck 15. A shaft 34 journals in the members 32 and carries the eccentrics 35 which are adjustably positioned by means of a hand lever 36 secured to the shaft 34 and capable of being held in a fixed position by a quadrant 37 and spring latch 38.

Mounted on the upright posts 31 are the bearings 39 on which are tiltably hinged the channel member guides 40 whose upper ends 41 are provided with the arms 42 along which the lumber 29 slides as it is unstacked. Each guide 40 can stop against an eccentric 35 when the guide is in an inclined position.

Associated with each guide 40 is a knee 43 whose top side 44 is normal to the guide 40 and parallel with the arm 42. Each knee 43 is provided with rolls 45 to reduce the friction. Each knee 43 has attached thereto an elongated lift arm 46 provided with stops 47 and 48 which engage the lever 49 of a toggle switch 50 which controls the motor 51 of the transmission 51—A, whose power take-off shaft 52 is provided with a

sprocket wheel 53 whose chain 54 passes around a sprocket wheel 55 secured on the shaft 56 which journals in the bearings 57.

The lower end 58 of each lift arm 46 is attached to a roller chain 59 which passes over the sprocket wheel 60 also secured on the shaft 56.

A counterweight 61 is attached to the lower end of the chain 59 within the well 62. The counterweights 61 are sufficient to support the load of the knees 43 and their attached parts, and if desired, a portion of the load 29.

For the purpose of illustrating a typical form of application, there is shown the screw rolls 63 which are supported by the frames 64 which also supports the guide 65. The screw rolls 63 move the pieces of lumber 29 toward the guide 64 and toward the planer or other machine (not shown).

The position of the foot operated switches 66 and 67 are also indicated.

The operation of the machine is as follows:

Assuming that the package 28 is placed on the bunks 27 and rests on the floor chains 26, and that these are being operated in the direction indicated on the drawings, and that they finally are entirely supported by the live rolls 17, the operator then causes the rolls 17 and the floor chains 26 to stop by manipulating a switch (not shown), which controls the operation of the floor chains 26. Then by depressing the foot operated switch 66, he causes the motor 51 to operate in a direction to lower the weight 61 and raise the lift arms 46, carrying with them the knees 43 and their load of boards 29 as shown in Fig. 5, during which time the various tiers of boards 29 slide down along the arms 42 and are carried by the screw rolls 63 to the planer.

If the relationship between the angularity of the arms 42 and the smoothness of the finish on

the boards 29 is such that they will not slide freely, the operator, either or both, increases the angularity by adjusting the cam 35 or by interrupting the action of the motor 51 in order to produce a shake or jar to the lift.

When the lift arms 46 reach their uppermost position, that is when the last tier of boards 29 has moved down across the arm 42, then the arm 48 trips the switch and stops the motor 51. In order to lower the knee 43, the operator must now depress the button 67 thereby reversing the motor 51 until the stop 47 actuates the switch lever 49 and again stops the motor 51.

It is a well known fact that the arts contain many elevating and tilting mechanisms. It is therefore not my intention to cover such devices broadly, but I do intend to cover only such forms and modifications thereof as fall fairly within the appended claims.

I claim:

1. The combination of a tiltable guide, a knee slidably mounted on said guide having its load engaging side normal thereto, a lift arm attached to said knee on one side of its center of gravity away from the direction of tilt, means for actuating said lift arm whereby the first portion of its lifting action will tilt said guide and the further movement of said lift arm will cause said knee to move upwardly along said guide.

2. An unstacker for lumber consisting of a tiltable upright guide hinged at its lower end, a knee slidably mounted on said guide and normal thereto, a lift arm attached to said knee between the unguided side and center of the knee, a counterweighted actuator for said lift arm, and means for operating said actuator.

WALTER H. BEANE.
